United States Patent Office.

PETER THOMPSON, OF SARDIS, OHIO.

Letters Patent No. 79,087, dated June 23, 1868.

IMPROVED SHOE-LASTER.

The Schedule referred to in these Letters Patent and making part of the same.

TO ALL WHOM IT MAY CONCERN:

Be it known that I, PETER THOMPSON, of Sardis, in the county of Monroe, and State of Ohio, have invented a new and improved Shoe-Laster; and I do hereby declare that the following is a full, clear, and exact description thereof, which will enable those skilled in the art to make and use the same, reference being had to the accompanying drawings, forming part of this specification.

This invention relates to an improvement in pincers for lasting shoes, or for other purposes, and consists in combining four jaws, which are operated by the ordinary pincer-handles or levers, in the manner hereinafter described.

The drawing represents a longitudinal sectional side view of my improved implement.

A represents the levers, which are connected together by the ordinary fulcrum-pivot, as seen at B.

The joint at the fulcrum may be made by halving the levers, or by lapping one over the other, or in any other suitable and convenient manner.

Thus far the construction is the same as the ordinary single pincers, but I duplicate the jaws (or the short ends of the levers A') by attaching thereto (by halving or otherwise) jaws C C, which also act as levers which have their fulcrum at D.

These jaws C are shaped so as to close upon the outsides of the lever-jaws A, as seen in the drawing, and so that these pieces of leather may be gripped or held separately by the four jaws combined, as shown, at the same time.

The inner ends e of the jaws C are pressed inward, and the jaws closed by springs f.

When the handles A A are pressed together, the movement will force the springs f against the tails e e, of the jaws C C, so that all four of the jaws will close simultaneously, and hold pieces of leather or other material with a strength of grip proportioned to the force applied to the handles A.

I claim as new, and desire to secure by Letters Patent—

In combination with the pincers or parts A A', the jaws C C and springs f f, constructed, arranged, and operating substantially as shown and described.

The above specification of my invention signed by me, this 14th day of March, 1868.
